UNITED STATES PATENT OFFICE.

GEORGE C. HAWLEY, OF ROCHESTER, NEW YORK.

SNOWPLOW.

Application filed September 1, 1921. Serial No. 497,613.

To all whom it may concern:

Be it known that I, GEORGE C. HAWLEY, a citizen of the United States, residing at Rochester, in the county of Monroe and State of New York, have invented certain new and useful Improvements in Snow-plows, of which the following is a specification.

The object of this invention is to provide 10 a new and improved type of snow plow for use on railroads or street railways.

This and other objects of this invention will be fully illustrated in the drawing, described in the specification and pointed out 15 in the claims at the end thereof.

In the accompanying drawing:

Figure 1 is a side elevation of the snow plow.

Figure 2 is a top plan view of the snow 20 plow.

Figure 3 is a front elevation of the snow plow.

Figure 4 is a detail view of one of the elevating screws used in the snow plow.

25 In the several figures of the drawing like reference numerals indicate like parts.

The snow plow forming the subject matter of this invention comprises a suitable car body 1 which is mounted on the car 30 trucks 2 and 3. At the front of the car body is provided the incline 4 which projects forwardly and downwardly therefrom to the track 5.

The front end of the car is provided with 35 the vertical casing 6 formed by the sides 7 and 8 and the back 9. The front of this casing is left open to permit the snow scooped up by the incline 4 to freely enter thereinto. Mounted to rotate in the casing 40 6 are a pair of vertical screws 10 and 11. Each of these screws is mounted to rotate closely against the rear of the casing 6 which for that purpose is made up of a pair of curved vertical channels into which the 45 screws project, and in which they partially rotate as indicated in Figure 2.

Both of the screws are driven from a suitable motive power installed either in the car itself or furnished by the trolley or locomotive used for moving the plow. The 50 screws rotate in opposite directions, that is the screw 10 illustrated in Figure 3 rotates in a counter clockwise direction and the screw 11, rotates in a clockwise direction. 55 In this way the centrifugal force acting on the frame of the car body, due to the ro-

tation of each of the screws, is balanced as much as possible.

At the upper end each of the screws 10 and 11 is provided with an extension, 12 and 13 respectively. These extensions are curved rearwardly of the screw on which they are formed and form a paddle thereon. The top of the casing 6 is partially closed by the housing 14. This housing is 65 mounted on top of the car body at the extreme front thereof, and overhangs half of the top of the casing 6. Suitable bearings are provided in the top of the housing in which the upper end of screw 70 shafts are adapted to rotate.

On top of the car between the channels forming the rear of casing 6 are mounted the deflecting beams 15 and 16. These beams are hinged to a suitable post 17, and can be 75 swung into any angular position with relation thereto and the open top of the casing for a purpose that will presently appear.

The rear of the car is provided with the 80 quarters for the crew, suitable access being had thereto thru the door 18 or any other door that may be provided for this purpose. The top of the rear end of the car is shown elevated over the top of the front part of 85 the car to make it possible for the crew to oversee the plow and the snow filled track ahead of it during the operation thereof.

The operation of the snow plow is as follows:

The plow is pushed ahead of the locomotive of the trolley car into the snow banks formed on the track. In so doing, the snow ahead of the plow is scooped up by the incline at the front of the plow and forced 95 into the casing behind the incline. The snow entering the casing is then elevated by the screws which revolve therein, each screw operating to elevate the snow in the part of the casing in which it is rotated. Each of 100 the screws is made up of a spiral which encircles the shaft thereof 180° , in order to prevent any clogging up of the snow in the casing or forming a core in the casing with the screw revolving in the snow. Each of 105 the screws operates to quickly raise the snow scooped up by the incline until it reaches the curved paddles 12 and 13 formed at the top of each of the screws respectively. At 110 this point the housing arrests the upward motion of the snow. The paddles 12 and 13 then sweep the snow from the housing

against the deflecting beams, which can be set to the proper angle to deflect the snow thrown out by the paddles to one side of the plow as desired.

5 I claim:

1. In a snow plow, the combination of a car body adapted to run on tracks, a casing provided at the front of said car, a pair of conveyor screws mounted in said casing 10 each of said conveyor screws comprising a blade which encircles 180° of the axis of the conveyor, the blades of said conveyors working toward each other and being mounted to distribute their weight evenly on the 15 body of the car body, an incline leading from said casing forwardly and downwardly thereof, a paddle formed integral with each of said conveyor screws at the upper end thereof, said paddles being adapted to throw 20 the snow elevated by said conveyor screws to one side of said car body on the rotation of said screws.

2. In a snow plow, the combination of a car body adapted to run on tracks, a casing 25 provided at the front of said car, a pair of conveyor screws mounted in said casing each of said conveyor screws comprising a blade which encircles 180° of the axis of the conveyor, the blades of said conveyors working 30 toward each other and being mounted to distribute their weight evenly on the body of the car body, an incline leading from said casing forwardly and downwardly thereof,

a paddle formed integral with each of said conveyor screws at the upper end thereof, 35 said paddles being adapted to throw the snow elevated by said conveyor screws to one side of said car body on the rotation of said screws, a semi-circular casing at the top of 40 said screw and partially overhanging said screws, said casing being adapted to arrest the upward motion given the snow by said screws and allowing said paddles forming part of the screws to sweep the snow elevated to said casing to one side of said car 45 body.

3. In a snow plow, the combination of a screw, said screw comprising a spiral of 180 degrees, a paddle formed integral at the top of said spiral and being slightly curved back 50 over the top of said spiral.

4. In a snow plow, the combination of a car body, a pair of vertical conveyors mounted to rotate at the front of said car body, each of said conveyors comprising a half 55 of a spiral, an outwardly curved flange formed at the upper end of each of said half spirals, a housing surrounding said conveyors, said housing having an opening in the front thereof the full length of said 60 conveyors said casing having an opening at the top to uncover the rear half of the top of said conveyors.

In testimony whereof I affix my signature.

GEORGE C. HAWLEY.
